RODENT GUARD FOR GANGPLANKS

Charles H. Matson, New York, N. Y.

Application February 11, 1944, Serial No. 521,995

2 Claims. (Cl. 14—72)

This invention relates to a guard for the gang plank of ships to prevent the entrance of rats or other rodents to the ships by means of gang planks, thereby preventing the loss and damage attributable to such rodents.

A particular object is to provide in connection with the gang plank, a means thereon which functions as a barrier or step and which is depressible as it is walked upon and which automatically restores itself to guard position when relieved of such weight of the walker.

The more particular objects and advantages will become apparent from a consideration of the description following taken in connection with accompanying drawings illustrating an operative embodiment.

In said drawings:

Figure 1 is a view showing a gang plank equipped with my invention, the gang plank being in longitudinal section;

Figure 2 is a cross section taken on the line 2—2 of Figure 1;

Figure 3 is a view partly cut away, in cross section with the parts depressed;

Figure 4 is a section taken on the line 4—4 of Figure 3; and

Figure 5 is a detail section taken on the line 5—5 of Figure 4.

Referring specifically to the drawings wherein like reference characters designate like or similar parts, my improvements are shown in connection with a conventional gang plank as used for ships and as suggested at 10. Such gang plank has a floor 11, side walls at 12 rising therefrom and hand rails 13 surmounting the latter. On the floor 11, at suitable intervals, usual battens or cleats 14 may be secured.

The improved guard includes a step or platform 15 adapted for vertical movement, the same having battens 16 at the ends thereof which are connected at the top by a bar 17 whose ends have projections 18 disposed between pairs of vertical guides 19 secured against the inner surfaces of the side walls 12 as at 20.

A base 21 preferably is provided and suitably secured to the floor 11. Pairs of collapsible panels 22 are hinged together as at 23 and are respectively hinged as at 24 and 25 to the step 15 and the base 21. It will be noted that the edges of the panels 22 are inclined and hence the pairs 50

of panels at the opposite sides of the guards are normally in inwardly extending V-formation and are urged to that position by suitable expansive spring means, specifically shown by way of example as U-shaped spring elements 26 whose terminals are secured at 27 to the step 15 and base 21. Such springs 26 at their bights, preferably have one or more coils 28.

As a result of the construction described, the 10 step or guard is normally raised and in the position of Figures 1 and 2, thus constituting a guard or barrier to the entrance of rats along the gang plank and onto the ship. It is also to be noted that the step and panels are relatively close to the side walls of gang planks at their ends so as not to provide sufficient space for passage of the rodents therethrough. In moving on or off the gang plank, the walker will tread upon the step 15 which will, under his weight, automatically move from the position of Figure 1 to the depressed position of Figures 3 and 4, and after treading thereon, the step will be immediately restored to elevated or guarding position through the expansion of the springs.

Various changes may be resorted to provided they fall within the spirit and scope of the invention.

I claim as my invention:

1. In combination with a gang plank, a step 30 slidably mounted thereon for vertical movement, panel means pivoted together, to the floor and to the step, spring means between the floor and panel means urging the latter to its uppermost position, said panel means being at the front and rear of the step and including parts forming inwardly extending converging portions.

2. In combination with a gang plank, a step 40 slidably mounted thereon for vertical movement, panel means pivoted together, to the floor and to the step, spring means between the floor and panel means urging the latter to its uppermost position, said panel means being at the front and rear of the step and including parts forming inwardly extending V's, ways provided on the side walls of the gang plank, a bar carried by the step and extending into said ways to guide the step in its vertical movement.

CHARLES H. MATSON.
